Levittage,

WITNESS:

Otto F. Werling, INVENTOR
BY *Victor J. Evans*

ATTORNEY

UNITED STATES PATENT OFFICE.

OTTO F. WERLING, OF WATERLOO, IOWA.

SANITARY CAN.

Application filed September 15, 1924. Serial No. 737,864.

The object of my said invention is the provision of a seamless and sanitary can for milk and the like, susceptible of being economically manufactured, and well adapted to withstand the rough usage to which cans are ordinarily subjected.

To the attainment of the foregoing, the invention consists in the improvement as hereinafter described and definitely claimed.

10 In the accompanying drawings, forming part of this specification:—

Figure 1 is a diametrical section of the can constituting the preferred embodiment of my invention.

15 Figure 2 is a top plan view of the same.

Figure 3 is a horizontal section taken in the plane indicated by the line 3—3 of Figure 1.

20 Similar numerals of reference designate corresponding parts in all of the views of the drawings.

My novel can comprises a body 1, a base 2 and a closure member 3. All of these are formed of heavy drawn or stamped steel, and

25 after the body and base are joined in the manner hereinafter described, they are heavily tinned to prevent rusting as is also the closure member 3. Being formed as described, it will be manifest that the body, 30 base and closure member will be devoid of soldered seams or riveted seams, and hence will be devoid of any unsanitary cracks or crevices in which milk or the like can be deposited. It will further be appreciated

35 that by virtue of the manner described in making my novel can, the can may be economically produced and yet is calculated to have a longer period of usefulness than an ordinary can.

40 The base 2 is provided with a concavo-convex bottom 4 and with an upstanding fold 5 and a pendent flange 6, and it is joined to the lower end of the body 1 through the medium of a weld 7 which is ground 45 smooth so as not to offer any projection or to afford any crevices for the collection of milk or the like.

The body 1 is shouldered at 8 and is provided with an upstanding neck 9 which may 50 be and preferably is beaded at its upper end as illustrated. By preference handles 10 are

riveted or otherwise fixed to the shoulder portion 8 of the body 1. The closure member 3 is provided with a vertical wall formed to follow the curvature of the neck 9 and is 55 further provided with a bottom and a curved upper edge to overlie and engage the bead of the neck as shown and in the closure member is appropriately fixed a diametrical handle 11 secured to the vertical wall above 60 the center thereof.

For the sake of enabling the base 2 to withstand rough handling, a heavy metallic reinforcing ring 12 is arranged within and against the flange 6 and is riveted thereto 65 as designated by 13.

It will be apparent from the foregoing that my novel can is sanitary, and yet is susceptible of being economically manufactured in such manner that the can will be 70 strong and durable and therefore adapted to last in good condition for a considerable period of time.

I have specifically described the preferred embodiment of my invention in order to impart an exact understanding thereof. It is to be understood, however, that I do not desire to confine myself to the specific construction and relative arrangement of parts in the present disclosure inasmuch as my invention is defined by my appended claims within the scope of which changes may be made without departure from my invention.

Having described my invention, what I claim and desire to secure by Letters-Patent, 85 is:—

A can of the character described comprising a steel body, a steel base having a concavo-convex bottom, an upstanding fold formed with said bottom, a depending flange 90 extending from the fold and having portions thereof arranged in contacting engagement with said fold, a weld interposed between and joining the opposed portions of the body and base at the bight of the fold 95 and being reduced to a smooth state, and said base being equipped with a heavy metallic ring arranged within and being fixedly connected to the pendent flange.

In testimony whereof I affix my signature.

OTTO F. WERLING.
